UNITED STATES PATENT OFFICE.

CHARLES S. PALMER AND DEAN PALMER, OF SARANAC LAKE, NEW YORK.

ELECTRIC IRON.

1,231,056.

Specification of Letters Patent.

Patented June 26, 1917.

Application filed December 18, 1916. Serial No. 137,550.

To all whom it may concern:

Be it known that we, CHARLES S. PALMER and DEAN PALMER, citizens of the United States, residing at Saranac Lake, in the 5 counties of Essex and Franklin, respectively, and State of New York, have invented a certain new and useful Improvement in Electric Irons, of which the following is a specification, reference being had

10 therein to the accompanying drawings.

Our invention relates to electrically heated flat irons or devices of a similar nature and has for its object to provide improved automatic means for controlling the 15 supply of current to the heating element of the iron so that the iron is particularly adapted to perform the services required of it in an effective and efficient manner without danger of scorching or setting fire 20 to inflammable material owing to the negligence or inadvertence of the user. The iron embodying our invention is designed to be automatically supplied with heat when in use or when placed on end in a position in 25 which the ironing surface is out of contact with surrounding objects so that the necessary heat may be maintained in the iron between ironing operations without the necessity of using a stand or the like, and is 30 further designed to automatically cut off the heat from the heating element when the iron is left on its ironing surface in a position in which it would otherwise do injury to inflammable objects such as fabrics or 35 the like.

A further object of our invention is to provide a very simple and inexpensive device which may be readily and cheaply produced and which is efficient and positive in 40 its operation.

Our invention will be fully understood from the following description taken in connection with the accompanying drawings and the novel features thereof are 45 pointed out and clearly defined in the claims at the close of this specification.

In the drawings, Figure 1 is a side elevation of a device embodying our invention.

Fig. 2 is an end elevation of the same.

50 Fig. 3 is a side elevation of the device shown in Figs. 1 and 2, the automatic mechanism being shown in the position it assumes when the device is in use.

Fig. 4 is an elevation showing the device 55 resting on end on its support.

Fig. 5 is a detail enlarged of the switch mechanism.

Fig. 6 is a side elevation partly in section of a modified form of device embodying our invention.

60 Fig. 7 is a view similar to Fig. 6 showing the switch lever pressed down against the handle as when in use.

Fig. 8 is an elevation showing the device resting on end.

65 Fig. 9 is a side elevation of another modified form of device embodying our invention.

Fig. 10 is a view similar to Fig. 9 showing the position taken by the switch lever 70 when the iron is in use.

Fig. 11 is a side elevation of the device shown in Figs. 9 and 10 resting on end.

Fig. 12 is a section on line 12-12 of 75 Fig. 9.

Having reference to the drawings there is shown a flat iron A provided with a base or ironing surface B which is heated by any well known means, not shown, such as one or more electric coils of usual form. At C 80 is shown a handle with which the iron A is provided. Between the iron A and its handle C is a connecting brace D, by which one end of the handle is secured to the iron, and a connecting brace E, which serves to secure 85 the other end of the handle to the iron and also as a receptacle for the switch mechanism to be hereinafter described. The base B is provided at its rear end with a member 11 which is of non-heat conducting material 90 and preferably extends from the lower end of the base B to the upper end of the handle as shown.

At the lower end of the member 11 a member 12 is pivotally connected, as shown at 95 13, which extends about the rear end of the iron A and over the top of the handle as shown, having a rear portion 14 and a forwardly projecting portion 15. The member 12 serves both as a lever for operating the 100 switch mechanism, in a manner to be described, and also as a support upon which the iron may rest when it is desired that it should be heated when not in use. For this purpose the portion 14 of the member 12 is 105 relatively broad, being preferably shaped as shown in Fig. 2, and the forwardly projecting portion 15 or hand member of the lever is provided with lips or flanges which are preferably curved to fit about the handle C 110

so that the lever may be readily grasped by the operator together with the handle C when the device is in use. Between the hand member 15 of the member 12 and the handle C is a spring 16 which tends normally to hold the portion 15 away from the handle, a stop 17 being provided to limit the action of said spring. The member 12 thus forms a lever which is pressed downwardly against the handle by the hand of the user when the necessary ironing pressure is exerted and which is moved away from the handle about the pivot 13 by the spring 16 when the handle is released by the operator and the device is not in use. The member 12 also operates as a lever when the iron is turned on end on the rear portion of the lever or rest 14, in which case the weight of the iron causes the spring 16 to be compressed and the portion 15 to be moved toward the handle as shown in Fig. 4. At 18 is shown a stop secured to the rear end of the handle C and adapted to contact with the portion 14 of the member 12 so as to limit the inward movement of the member.

A snap-over switch is preferably located within the member E and consists of an actuating plunger 19 of non-conducting material such as vulcanite or the like, of a movable contact lever 20, a spring contact 21, and a fixed contact 22, the last mentioned member being connected to suitable heating coils not shown by a wire 9. The spring contact 21 and the heating coils are connected with the supply by wires 7 and 8 respectively. The plunger 19 projects through a hole in the member 11 into the switch box or member E, and is pivotally connected at its outer end with the portion 14 of the member 12. The plunger 19 also passes through an elongated opening 27 in the lever 20, which is pivotally mounted at 28, and is provided at each side of the lever 20 with enlarged portions 25 and 26. A pair of light springs 29 and 30 surround the plunger 19 and are interposed between the enlarged portions 25 and 26 respectively and the contact lever 20. The contact 22 is fixedly mounted in the switch box or member E and is so arranged that the lower end of the lever 20 makes contact with it when the plunger 19 is pressed inwardly and the lever 20 is thrown into the position shown in dotted lines in Fig. 5. The spring contact 21 is curved as shown in Fig. 5 and is secured at one end at 31 to the switch box E, and projects over the upper end of the lever 20 in a position to always be engaged by the same. The springs 29 and 30 and the spring contact 21 are so arranged that when the plunger 19 is pressed inwardly by the lever 12 the spring 30 will be compressed until the pressure exerted by it overcomes the pressure exerted by the spring 21 against the end of the lever 20. The lever

20 will then be snapped past the lowermost portion of the curved spring 21 into the position shown in dotted lines in Fig. 5. When in this position the spring 29 operates to hold the lever 20 in contact with the spring 21. When the lever 12 is moved outwardly by the spring 16, which is stronger than springs 29, 30 and 31, the reverse operation to that described above takes place and the lever is snapped back into the position shown in full lines in Fig. 5 and out of contact with the member 22. While we have shown the form of snap-over switch preferred we do not desire to limit ourselves to this particular form of construction.

We regard this as one of the important features of our invention for a snap-over switch used in combination with the lever 12 as shown enables a quick break of the circuit to be affected, and furthermore insures a constant contact and consequent steady supply of current to the heating element at all times while the iron is in use regardless of slight variations in pressure occasioned by varying the weight of the hand in ironing. The device is preferably adjusted so that the contact is broken only when practically the entire pressure is removed from the handle. In this way a continual making and breaking of the connection is prevented, the resulting wear and tear on the parts is eliminated, and a constant heating current is obtained.

It will be seen that the device hereinabove described may be used without danger of overheating, scorching or setting fire to inflammable materials, for whenever the operator lets go of the handle the current is automatically cut off in the manner described. If on the other hand it is desired to maintain heat in the iron when not in use it is merely necessary to place it on end on the rest 14 as shown in Fig. 4 and the weight of the iron will move the member 12 inwardly against the spring 16 and throw the switch into engagement with the fixed contact 22 thereby supplying current to the heating element when the ironing surface is free from contact with surrounding objects.

Having reference now particularly to Figs. 6, 7 and 8 there is there shown a modified form of device embodying our invention. The iron F is similar to the iron A described above but is provided with a different form of automatic mechanism for controlling the supply of current to the heating element. The mechanism is also so arranged that current is supplied to the heating element of the iron when in use and when placed on end as shown in Figs. 7 and 8 respectively, but is not supplied to the heating element when the iron is not in use and allowed to remain on its base or ironing surface.

The control mechanism consists of a lever

33 which is pivoted at one end to the handle G of the iron as shown, and at the other end is engaged by a plunger 34 which is surrounded by a spring 35 interposed between the head of the plunger 34 and the inner end of a pocket 36 in the handle G and tending normally to hold the plunger in raised position as shown. The plunger, the upper end of which consists of non-conducting material, passes loosely through a hole in the handle G and projects downwardly through a hole in the upper surface of a container 37. The plunger makes a snug sliding fit in the hole in the container 37 and is adapted to extend well down into the container as shown in Fig. 7 when pressure is placed on the lever 33 by the user of the iron. The container or switch box 37 consists of suitable non-conducting material such as vulcanite or the like and is provided, at its lower end, preferably at the place shown in the drawings, with a terminal 38 to which is connected a wire 39 leading to the heating element from which a wire 61 leads to the source of supply. A wire 40 also leading from the current supply passes through the rest 41, provided at the back of the iron, and is secured to the non-insulated portion of the plunger 34. Within the container 37 is a quantity of mercury 42, or other suitable current conducting liquid, into which the plunger 34 is adapted to dip when pressed down by the user of the iron and out of which the plunger is lifted by the spring 35 when the iron is not in use. When the iron is in use and the lever 33 is pressed downwardly, current passes between the wires 40 and 39 by way of the plunger, mercury, and terminal 38 thereby supplying current to the heating element, and when the plunger is raised the circuit is broken and the heat cut off. The plunger fits sufficiently snugly in the hole in the container to substantially seal the container and prevent the escape of the mercury or mercury gas occasioned by the passage of current.

If it is desired to maintain heat in the iron while not in use and when it is in a position in which it can do no injury to inflammable materials the iron is placed on end on the support 41, which is of non-heat conducting material, and the plunger 34 and the terminal 38 are both submerged in the mercury thereby making the circuit and permitting the current to pass to the heating element.

Still another modified form of device is shown in Figs. 9, 10, 11 and 12 in which the automatic mechanism consists of a lever 43 pivoted at one end of the handle, a spring mounted plunger 44 slidably mounted through the handle and pivotally connected to a sealed L-shaped container 45, provided with trunnions 46, mounted in suitable brackets of non-conducting material secured

to the handle of the iron. The trunnions 46 form terminals one of which is connected to the source of supply by a wire 50 and the other of which is connected to the heating coils not shown, and thence with the supply by wires 49 and 62 respectively. When the spring mounted plunger 44 is pressed down by the lever the container 45 is swung about its pivot from the position shown in Fig. 9 to the position shown in Fig. 10. The container is partially filled with mercury, or like liquid 63 which remains in the lower end of the container when the iron is resting on its base or ironing surface and not in use.

When the iron is in use the hand of the user presses the lever 43 downwardly against the handle and tilts the container 45 into the position shown in Fig. 10 which causes the mercury to flow into the opposite end of the container and submerge the terminals 46 thereby allowing current to pass to the heating element. When the iron is placed on end on the rest 48 the mercury in the container submerges the terminals 46 and thus affords a supply of current to the heating element. In this way the heating element of the iron is supplied with current when in use and when resting on one end, but the current supply is cut off if the iron is allowed to remain on its base when not in use so that all danger of scorching or setting fire to inflammable materials is eliminated.

What we claim is:

1. The improved electric iron having an operating surface and a heating element, a support secured to said iron, and automatic means arranged to permit the supply of current to the iron when in use and when on its support.

2. The improved electric iron having an operating surface and a heating element, a support secured to the iron, a switch by which the supply circuit is normally broken, and means operated to complete the circuit when the iron is in use when on its support.

3. The improved electric iron having an operating surface and a heating element, a support secured to said iron, said support being arranged to hold said iron with its operating surface free from contact, and automatic means arranged to permit the supply of current to the iron when in use and when on its support.

4. The improved electric iron having an operating surface and a heating element, a portion of said iron being arranged to form a support, and automatic means arranged to permit the supply of current to the iron when in use and when on its support.

5. The improved electric iron having an operating surface and a heating element, a support movably mounted on said iron, and means operated by said support for supplying current to the iron when in use and when on said support.

6. The improved electric iron having an operating surface and a heating element, a lever pivotally mounted on said iron one portion of which forms a support therefor 5 and another portion of which forms a hand member, said lever being adapted to be moved about its pivot both by the hand member portion and the support portion, and means operated by said lever for supplying 10 current to the iron.
7. The improved electric iron having an operating surface and a heating element, a pivoted lever mounted on said iron, a portion of which forms a support for the iron and a 15 portion of which forms a hand member adapted to be grasped by the operator when using the iron, a spring by which said lever is actuated in one direction, and means operated by said lever for supplying current 20 to the iron when said spring is compressed.
8. The improved electric iron having an operating surface and a heating element, a lever forming a support and a hand member, the support being pivotally mounted 25 at one end to said iron and the hand member being adjacent the handle of the iron, a spring tending normally to hold the lever away from the iron, and means operated by
- 30 said lever for supplying current to the iron when said spring is compressed.
9. The improved electric iron having an operating surface and a heating element, a lever pivoted at one end to the rear of the iron and forming both a support and a hand member, a spring engaging said lever, a 35 switch for controlling the supply of current to the heating element, and a member by which said lever and switch are connected.
10. In an electric iron, the combination of 40 a lever movable in one direction by hand, a spring which moves the lever in the reverse direction, and a snap-over switch having a movable member operated by said lever which breaks the circuit when the lever is 45 in its normal position and which closes the circuit when the lever actuating spring is compressed, the parts being so arranged that the switch is snapped into circuit breaking position only after the first part 50 of the movement of the lever against its spring has been completed.

In testimony whereof we affix our signatures.

CHARLES S. PALMER.
DEAN PALMER.
